UNITED STATES PATENT OFFICE.

JAMES P. NORWOOD, OF CHICAGO, ILLINOIS.

RAILWAY-SIGNAL.

No. 821,952.

Specification of Letters Patent.

Patented May 29, 1906.

Application filed June 23, 1905. Serial No. 260,500.

To all whom it may concern:

Be it known that I, JAMES P. NORWOOD, a citizen of the United States, residing at Chicago, county of Cook, and State of Illinois, have invented a certain new and useful Improvement in Railway-Signals, of which the following is a specification.

My invention relates to a new and useful improvement in railway-signals, and has for its object to provide a device of this description in which the indicating-registers are located in stations along the road and at the terminals and also in the trains, which will indicate the position of different trains upon the road at all times.

With these ends in view this invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawings, forming a part of this specification, in which—

Figure 1 is a plan view of one of the registering devices; Fig. 2, a side elevation of the same; Fig. 3, an end elevation of the register, a portion of the same being shown in section; Fig. 4, a cross-section taken on the line 4-4 of Fig. 2; Fig. 5, a diagrammatical view of a portion of the road, showing two trains approaching one another upon the same block; Fig. 6, a diagrammatical view of a road from one terminal to the other, showing the arrangement of wire and showing the road divided into blocks.

The purpose of my invention is to show by electrical means the exact movement of the trains of a certain road, the indicators showing these movements being located at distant points, and there also being indicators located upon each train which will not only indicate the movement of the train itself, but of any other train moving toward it upon the same road.

A represents the railroad-rails, and upon each side of the road-bed are located two auxiliary rails B and C, which are insulated from one another and also from the road-bed.

D represents the trains traveling upon the road, and in each train are arranged two electrically-operated devices E. Each regis-

tering device E is electrically connected to two shoes B' and C', which are adapted to travel in constant contact with the auxiliary rails B and C, respectively. One terminal of the electrical devices in the registering devices is connected to the shoe C' and the other terminal to the shoe B'. Upon each train is located a source of electricity consisting of either a battery or dynamo, (represented at F,) and one terminal of the source of electricity is connected to a shoe C', traveling in constant contact with the auxiliary rail C upon one side. The shoe C' in the oppositely-moving train will of course be in contact with the auxiliary rail C upon the opposite side of the track. The other terminal of the source of electricity is electrically connected with a shoe G, which is arranged to travel outside in juxtaposition but not in contact with one of the auxiliary rails B. The auxiliary rails B are provided at certain equal intervals with short contact-strips H electrically connected to the rails B. These contact-strips lie within the path of travel of the shoes G, and when the shoes G strike these contact-strips it will be seen that the electric current from the source of electricity F will pass to the shoe C' through the rail C, through any of the registers connected to the rails C and B, back through the shoe G to the other terminal of the source of electricity. Thus all of the registers connected to the rails B and C will be operated each time the shoe G strikes a contacting strip H. Of course as "shoes" it is obvious that any other form of traveling contact could be used, such as wheels or the like.

In each regular station along the road two registering devices would also be located, one connected to the two auxiliary rails B and C upon one side of the track and the other connected to the auxiliary rails B and C upon the opposite side of the track, as shown in Fig. 5. The registering devices E, located upon the trains, are also connected to the opposite auxiliary rails, so that one of the registers in each train would show the progress of the train upon which the register is located, and the other register would show the progress of the next train in front traveling in the opposite direction, so that all head-on collisions would be avoided, for each train would be notified of the exact position of the train immediately in front of it traveling in the opposite direc-

tion, and telephone arrangements could be located in each train and in each station, if desired, which could be cut into the line, so that any station or any two trains could talk 5 one with the other. In order to avoid rear-end collisions, the auxiliary rails are divided into sections or blocks, and at the break or division between the sections of the auxiliary rails are located local stations, in each of 10 which are located four registering devices, two of which are electrically connected to the two pairs of auxiliary rails in one block, and the other two are electrically connected to the two auxiliary rails in the next block. Thus 15 any two trains traveling in the same direction are allowed upon one block at the same time, the local stations governing this.

In each terminal of the road or division is located one register for each pair of auxiliary 20 rails in each section or block. Thus the registers at the terminals will show the movement of all trains upon the road. The registers in the local stations will show the movement of all trains upon two adjacent blocks, and the 25 registers in the regular stations and upon the trains will show the movement of two trains traveling in opposite directions upon the same block. Opposite each regular station and arranged upon each side thereof are two 30 contact-strips, considerably longer than the other contact-strips, as represented at H', so that when the shoe G strikes and travels these long contact-strips the registers will be operated a longer length of time, and I have pro- 35 vided in these registers mechanism which, if operated a certain length of time, will indicate a record upon a time-disk, thus recording the time at which a certain train reached and left a certain station. The mechanism 40 for accomplishing this will be described in connection with the register.

In Figs. 1, 2, 3, and 4 the registering apparatus is illustrated, which consists of a magnet or magnets I, which are electrically connected to the auxiliary rails B and C, as before described, either directly, as in the case of stations, or through traveling contacts when the register is located upon the trains. J is a lever pivoted intermediate of its two ends at 45 the point J', and to this lever, upon one side of the pivot, is secured an armature J², adapted to be attracted by the magnet. J³ is a spring tending to force the armature away from the magnet. K is a ratchet-wheel journaled to 50 the framework of the register. K' is a pawl always in engagement with the ratchet-wheel, and said pawl is connected to the lever J, so that each time the lever J is operated by the magnet I the pawl will be moved so as to 55 cause the ratchet-wheel K to revolve a certain predetermined distance. L is a gear-wheel secured upon the same shaft as the ratchet-wheel K, and this gear-wheel meshes 60 with an elongated spur-gear M, secured upon the shaft N, journaled in suitable bearings to

the framework. O denotes beveled gears secured to the shaft N, and one of these beveled gears is always in mesh with a beveled gear O', journaled in suitable bearings secured to the framework and connected to an indicating-hand P, which hand rotates in front of a disk upon which the stations are indicated. The beveled gears O are located upon opposite sides of the beveled gear O' and at such a distance apart that when one is in mesh with the beveled gear O' the other is out of mesh, so that by sliding the shaft N backward and forward the direction of movement of the hand can be reversed, so that the same indicator can be used, no matter in what direction the 80 train is traveling. Thus it will be seen that each time the contact-shoe G comes in contact with the contact-strips H the magnets I of all of the registers connected to the auxiliary rails of that particular block are energized, thus attracting the armatures J², thus operating the train of gears, so that the indicating-hand is moved a certain distance on the dial, and when any regular station is reached the indicating-hand will be opposite 85 the name of that station upon the dial. Thus the position of the trains can be ascertained at any time. Q is a timepiece to the armature of which is secured a dial Q' instead of the ordinary hands, so that the dial revolves. 90 This dial is made of material easily perforated, and arranged above the periphery of the dial is a pointed rod R, pointed at its lower end, which passes through and is guided within a tube R', in which is arranged 95 a spring R², normally holding the rod R above the dial. S is a horizontal flat spring secured to a suitable standard, the free end of which lies above the upper end of the rod R in its normal position; but if said spring S 100 is raised and then allowed to fly back it will strike the upper end of the rod R and force the point of the rod downward into the dial, making an indentation or perforation, and secured to the other end of the lever J and 105 journaled thereon is a gear-wheel T, and secured to this gear-wheel is an arm T', the weight of this arm being sufficient to revolve the gear-wheel T and allow the arm to always hang downward in a vertical position; 110 but if the gear-wheel and arm are revolved over one-quarter of a revolution said arm will strike the under side of the spring S and raise the same, and as soon as it passes the 115 spring said spring will fly back and operate the perforated rod R. U is a spring-motor adapted to drive a shaft V. Journaled in suitable bearings upon this shaft is secured a gear V', with which the gear-wheel T is adapted to mesh when the lever J is operated 120 through the magnet I. W is a notched wheel, also secured upon the shaft V, and W' is a lug connected to the lever J, adapted to engage one of the notches in the notched 125 wheel W and hold the shaft V against rev- 130

lution by the spring-motor when the lever J is in its normal position with the armature J' out of contact with the magnet; but as soon as the magnet I is energized and the lever J rocked upon its pivot the wheel T will be thrown into gear with the gear V', and at the same time the lug W' will be drawn out of contact with the wheel W, allowing the motor U to rotate the shaft V, and thus the gear-wheel T will continue to be revolved as long as the magnet I is energized; but the short contact-strips H are of such a length that even with the slowest-moving train the shoe G would not remain upon the contact long enough to cause the wheel T to revolve one-quarter of a revolution; but when the shoe G strikes the elongated contacts H' the gear-wheel T will be revolved considerably more than a quarter-revolution, thus causing the arm T' to actuate the spring S, and thus cause the dial Q' to be perforated, thus indicating the time of the arrival of the train at that particular station. Thus it will be seen that I have provided an electrical system whereby the officials of the road, both at the stations, terminals, and on the moving trains, will be instantly informed of the locations of all of the trains, and the registers will record the time of arrival at any station of any train.

Of course any suitable registering mechanism could be employed which would accomplish the object which I desire, and I do not wish to be limited to this particular mechanism for the registering as herein described, as I am perfectly aware that I have shown it in a crude form, and it could be changed materially without departing from the spirit of the invention, and other features could be added to the register, if so desired, to make a permanent record of all trains at different times. Therefore I do not wish to be limited to the exact construction here shown, as slight modifications could be made without departing from the spirit of my invention.

Having thus fully described my invention, what I claim as new and useful is—

1. In a railway-signal, electrically-operated registers located in each train and in certain stations along the road, two auxiliary rails arranged upon each side of the road-bed, half of the registers in each train and station being connected in series with one pair of auxiliary rails and the other half being connected in series with the other pair of auxiliary rails, a source of electricity carried by each train, a traveling contact electrically connected to one terminal of the source of electricity adapted to travel in constant contact with one auxiliary rail of one pair, contacts electrically connected to the other rail of the same pair, a traveling contact electrically connected to the other source of electricity adapted to strike said

permanent contacts when in alignment with the same and thus operate the registers.

2. In a railway-signal, electrically-operated registers located in each train and in certain stations along the road and at the terminals, each of said registers provided with an indicator adapted to be moved one step each time the current flows through the register, two pairs of auxiliary rails extending parallel with the road insulated from the road-bed and from one another, permanent contact-strips electrically connected to one of the auxiliary rails in each pair and arranged equal distance apart, a source of electricity carried by each train, two traveling contacts connected in series with said source of electricity, one traveling contact adapted to travel so as to contact the permanent contacts when in alignment with the same, the other traveling contact traveling in constant contact with the other auxiliary rail of the same pair, said traveling contacts so arranged that they will contact one pair of auxiliary rails when the train is traveling in one direction and the other pair when the train is traveling in the opposite direction, half of all the registers being connected in series with one pair of auxiliary rails and the other half connected in series with the other pair of auxiliary rails, the permanent contact-strips located at the regular stations being longer than the other permanent contact-strips so that the current will be caused to flow a greater length of time when these strips are reached, means located in each register for recording the time, said means adapted to be only operated when the current is caused to flow a predetermined length of time.

3. In combination with a railroad-signal of the character described, an electrically-operated register consisting of an indicator, a movable member connected with said indicator, a magnet adapted to move said indicator one step when the same is energized, a timepiece located in the register, a removable dial connected with said timepiece and adapted to revolve a perforator arranged above the dial, a spring-motor arranged within the register, means connected with said spring-motor adapted to operate the perforator so as to cause the same to perforate the dial, and means adapted to prevent the spring-motor actuating the perforator only when the magnet remains energized a predetermined length of time, as and for the purpose specified.

In testimony whereof I have hereunto affixed my signature in the presence of two subscribing witnesses.

JAMES P. NORWOOD.
